ATTORNEY

UNITED STATES PATENT OFFICE.

ERIK J. JANSEN, OF BELLAIRE, OHIO.

MIRROSCOPE.

1,258,339.

Specification of Letters Patent.

Patented Mar. 5, 1918.

Application filed August 26, 1916. Serial No. 117,094.

To all whom it may concern:

Be it known that I, ERIK J. JANSEN, a subject of the King of Denmark, residing at Bellaire, in the county of Belmont and 5 State of Ohio, have invented certain new and useful Improvements in Mirroscopes, of which the following is a specification.

This invention relates to mirroscopes and more particularly to a reflecting device 10 adapted to be arranged outside of a building whereby a person within the building may observe objects on the street in either direction by simply glancing in one of the mirrors carried by the device.

15 The principal object of the invention is to provide a pair of reflecting mirrors disposed at an angle to each other and pivotally mounted upon a bracket secured to the window frame whereby the mirrors may be 20 readily adjusted to any desired angle.

A further object of the invention is to provide a device of this character adapted for use on automobiles whereby the driver may observe persons or objects at opposite 25 sides of the automobile; the mirrors being pivotally mounted whereby the operator may observe objects approaching the intersection of streets or railways before turning a corner.

30 A further object of this invention is the provision of mirroscopes which consist of comparatively few parts and are simple in construction, but durable and well adapted to withstand the rough usage to which devices of this character are ordinarily subjected.

35 For a full description of the invention and the advantages and merits thereof, reference is to be had to the following description and the accompanying drawings, wherein is illustrated the preferred form of my invention, in which;

Figure 1 is a front elevation.

Fig. 2 is a plan view.

40 Fig. 3 is a fragmentary horizontal section on the line 3-3 of Fig. 1.

Fig. 4 is a vertical fragmentary section on the line 4-4 of Fig. 1.

45 Referring to the drawing, wherein is illustrated the preferred form of my invention, and in which like numerals of reference indicate corresponding parts throughout the several views, the device is provided with two mirrors 1 and 2 mounted in a 50 framework of substantially triangular con-

struction. The frame is preferably formed from sheet metal and comprises the rectangular frame member 3 and a similar frame member 4 joined together at one of their edges by a triangular brace 5 having its vertex curved as shown by Fig. 3 of the drawing and its side flanges 6 and 7 fastened to the edge 8 of each frame member 3 and 4. The opposite vertical edges of the frame members 3 and 4 are connected at 60 their upper and lower ends by the cross bars 9 arranged one above the other at the upper and lower edges of the frames 3 and 4. The mirrors 1 and 2 are thereby disposed at an angle to each other at substantially 65 60 degrees. A cylindrical bearing 10 is arranged directly above the V-shaped piece 5 and receives the pintle 11 vertically extending from a bracket arm 12 which is integrally formed with a depending flange 70 75 13 having openings for the reception of fastening screws whereby the bracket may be fastened to the window frame. Within the vertex of the inner faces of each of the frame members 3 and 4 is a reinforcing strip 14 fastened to the inner walls of the frame members 3 and 4 for effectively bracing the same.

As shown by Fig. 4 of the drawing, each frame member is formed from a sheet of material having a vertical flat rear wall 15 and the top and lower edges of the frame members are formed by lateral extensions 16 of the rear wall 15 which, in turn, is bent downwardly at the front and again inwardly to provide the retaining flange 17 which engages the front surfaces of each mirror.

55 In operating the device it is merely necessary to attach the flange 13 to a convenient part of the window frame whereby the device will be extended out over the sidewalk or thoroughfare, the extension arm 12 being of any desirable length.

The mirror may be then swung on the 100 pintle 11 until it is adjusted to the proper angle for observing the objects as they pass up and down the thoroughfare.

On an automobile the bracket is mounted at a convenient point on the body of the 105 machine within convenient reach of the driver whereby he may adjust the mirror to the angle desired to observe, through the medium of one of the reflecting surfaces, objects at one side and at the rear of the 110

automobile or adjust the other reflecting surface to observe objects at the other side of the automobile.

From the foregoing it will be observed 5 that a very simple and durable mirroscope has been provided, the details of which embody the preferred form. I desire it to be understood however, that slight changes in the minor details of construction may be 10 made without departing from the spirit of the invention or the scope of the claim hereunto appended.

I claim:

15 A mirroscope comprising a pair of mirrors disposed at an angle to each other, a frame for each mirror, two of the edges of the frame being held in close proximity to each other and provided with a brace member curved over the vertex of the edges of 20 the said frame to maintain the mirrors at

predetermined angles with respect to each other, the said brace member having flanges fixed to the adjacent portions of the said frame members independently of the said mirrors, the inner walls of the frame members having a reinforcing strip to coöperate with the said brace member for rigidly maintaining the said mirrors in properly spaced relation, the said curved portion of the brace member carrying a cylindrical 25 socket to support both of the said mirrors, and a bracket element adapted for reception in the said cylindrical socket to permit turning movement of the said mirrors.

In testimony whereof I affix my signature 30 in presence of two witnesses.

ERIK J. JANSEN.
